UNITED STATES PATENT OFFICE.

JOHN H. SAMPLE, OF TOLEDO, OHIO.

CHECKER BAR.

1,426,112.

Specification of Letters Patent. Patented Aug. 15, 1922.

Application filed January 10, 1921. Serial No. 436,066.

To all whom it may concern:

Be it known that I, JOHN H. SAMPLE, a citizen of the United States, and a resident of Toledo, in the county of Lucas and State of Ohio, have made an Invention Appertaining to Checker Bar; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention has for its object to provide a convenient checker bar for checking the dimensions of castings or patterns for articles or devices of different kinds with drawings or specifications.

20 The invention may be contained in structures of different forms, and to illustrate a practical application of the invention I have selected a checker bar containing the invention as an example. The checker bar selected

25 is shown in the accompanying drawings.

Figure 1 of the drawings illustrates a perspective view of the checker bar. Fig. 2 illustrates the checker bar and the manner of using it in checking a casting or a pattern.

30 1 in the figures is a bar, preferably made of metal, that is pivotally supported on a standard 2. It has a bracket 3, and a pivot pin 4 extends through the standard and the bracket 3. The pivot pin 4 may be provided with a handle 16 whereby the bracket 3 may be clamped in a slot formed in the standard 4, and the bar may thus be rigidly held in an upright position. One end of the bar extends beyond the standard 2 so that when

35 the bar 1 is raised to an upright position the end of the bar 1 will strike the head of the screw 5 which is threaded into the standard 2. The checker bar may thus be placed in a vertical or plumb line position by the

40 proper adjustment of the screw 5.

The checker bar is provided with a leg 6 which will place the checker bar in a horizontal position when the leg 6 is placed so as to rest on a table or other object on which

45 the standard 2 is placed. The leg 6 is slightly higher than the standard 2 so as to place the checker bar substantially in a horizontal position on the table. The checker bar may be provided with a blackened upper surface

50 7 by any suitable means such as by lamp black mixed with shellac or any other suit-

able material. The face, moreover, is deeply scored or grooved, as by the lines 8 to divide the face of the checker bar into a plurality of parts. This extends the utility of the 60 checker bar in that it avoids confusion of indicating lines. The spaces between the grooves and between the grooves and the edges of the checker bar may be used for checking different things, or different parts 65 of the same thing, or checking the same thing when put in different positions on a face plate. The face of the checker bar is blackened so as to render markings by compasses readily discernible.

The checker bar is also provided with a saddle 9 which extends around the checker bar and may be clamped in any position by means of the screw 10. The saddle has a plurality of pairs of holes, each pair being 70 usable for a space in which the face of the checker bar is divided. Some of the holes, such as the holes 11, extend but a short distance into the metal of the saddle, while the holes 12 extend through the metal of the 75 saddle. The holes 11 form recesses for holding one of the points of the compasses that are used to mark the checker bar off when the dimensions are taken from the drawing or from specifications, or from another article or object with which an article or object is to be compared. The holes 12 are sight 80 holes so as to place the saddle on a definite predetermined line that may be marked across the face of the checker bar or across 85 only one of the divisions of the checker bar. These lines are sometimes termed zero 90 lines, that is, they are the lines from which the measurements are taken, such as a center line of a shaft, or a center line of a casting. 95 When a center line has been determined, the measurements to certain points of the article to be produced are marked on the checker bar, and in order that a plurality of sets of such marks may be made preparatory to 100 checking the article produced with a blue print or a specification different zero lines may be used, and the different sets of markings may be placed in the different spaces of the face of the checker bar.

105 The checker bar is then placed on a face plate such as the plate 13, and a surface gauge 14 is set to any particular mark made on the checker bar. The point of the checker bar is then turned to the object, such as the 110 casting 15, to ascertain whether or not the casting has been correctly made, or has the

particular measurement specified. In this way the measurements of the different parts of the casting 15 may be checked.

I claim:

- 5 1. In a checker bar a standard, a bar pivotally supported by the standard, a saddle supported on the bar and having holes.
- 10 2. In a checker bar a standard, a bar pivotally supported by the standard, a saddle supported on the bar and having holes extending through the saddle, and holes extending a short distance into the metal of the saddle.
- 15 3. In a checker bar a standard, a bar pivotally supported by the standard, a saddle supported on the bar and having holes extending through the saddle, and holes extending a short distance into the metal of the saddle, the holes arranged in pairs, and the 20 checker bar having scorings extending the length of the checker bar, and located between the pairs of holes.
- 25 4. In a checker bar a standard, a bar pivotally supported by the standard, a saddle supported on the bar and having holes extending through the saddle, and holes ex-

tending a short distance into the metal of the saddle, the holes arranged in pairs, and the checker bar having scoring extending the length of the checker bar, and located between the pairs of holes, the surface of the checker bar being coated by a material to render scratches on the face of the checker bar discernible. 30

5. In a checker bar a standard, a bar pivotally supported by the standard, a saddle supported on the bar and having holes extending through the saddle, and holes extending a short distance into the metal of the saddle, the holes arranged in pairs, and the 40 checker bar having scorings extending the length of the checker bar, and located between the pairs of holes, the surface of the checker bar being coated by a material to render scratches on the face of the checker 45 bar discernible, an adjustable screw and a clamping means for securing the checker bar in upright position.

In testimony whereof, I have hereunto signed my name to this specification.

JOHN H. SAMPLE.
